UNITED STATES PATENT OFFICE.

HERBERT R. ELLIS, OF FREDERICKSBURG, VIRGINIA, ASSIGNOR OF ONE-HALF TO
STUART TANSILL, OF FREDERICKSBURG, VIRGINIA.

CHAIR ATTACHMENT FOR TABLES.

Application filed June 11, 1921. Serial No. 476,720.

To all whom it may concern:

Be it known that I, HERBERT R. ELLIS, a citizen of the United States of America, residing at Fredericksburg, in the county of Spotsylvania and State of Virginia, have invented certain new and useful Improvements in Chair Attachments for Tables, of which the following is a specification.

This invention relates to the class of furniture and more especially to a chair attachment for tables.

It is the object of the invention to provide a simple and novel structure of the above character which can be economically and easily manufactured, the device being particularly adapted for attachment to or to be manufactured with the table, of any of the well known types, such as those provided with a pedestal or corner legs, and to be used to seat or accommodate an infant or child in a comfortable and safe position at a table, in lieu of using a chair or other improvised means for the purpose, where a high chair is not kept or at hand because not ordinarily needed. However, it is to be understood that the invention contemplates the use of the same principle for older or grown persons, especially where it is desirable that the chairs or seats be out of the way when not in use.

Other and further objects of the invention will become apparent as the description proceeds, in view of which, it will be seen that the invention consists of certain novel combinations and arrangements of parts as will be hereinafter more particularly pointed out and claimed.

In the accompanying drawings:

Figure 1 is a side view of the chair or seat applied to a table, a fragmentary portion of the latter being shown in section, and in combination with which the chair forms a part,

Figure 2 is a similar view but showing the chair pushed in under the table, as distinguished from the extended position of the device shown in Figure 1 of the drawings,

Figure 3 is a front elevation of the device removed or detached from the table and with the supports thereof in section,

Figure 4 is an enlarged detail view, showing in vertical section, the table top or boards and the support for the seat, and

Figure 5 is a detail view showing another foot rest or board support and adjusting means.

Referring to the drawings in detail, 10 designates the table top or boards of the usual or any preferred construction having the drop ledge or frame 11 vertically 60 beneath the same spaced from the edge, in the usual manner, but provided with a cut-out or bottom recess 12. Beneath the top is secured in any suitable manner like the extension slides of an extension table, 65 either round or rectangular, a pair of slides or grooved supports 13, preferably having dovetailed grooves 14. These supports are arranged in parallel relation at a right angle to the recess, and slidably receive a pair of 70 slides or slidable supporting bars 15 having dovetailed extensions or tongues 16 slidably engaging the grooves 14 and together with the supports 13, constituting extension supporting means for the chair generally designated at 17.

It will be seen from an inspection of Figures 1 and 2 of the drawings, that the bars or arms 15 are slidable in the grooves or guideways 14, so as to extend outwardly 80 from or totally beneath the table or top thereof, and inwardly of the frame ledge or molding 11. This presents a long supporting bearing for the seat, easily applied and readily slidable, and it is desired to be understood that any suitable slidable support with or without anti-friction means or rollers may be provided for the purpose, in order that the bars or arms 15 will be supported for free movement and yet give a strong and 90 substantial supporting means for the seat so as to preclude sagging of the latter.

As shown, the bars or arms 15 move through the cut-out or recess 12, or the opening produced thereby, and being in spaced 95 parallel relation, are secured to the sides of the drawer-like seat attachment proper or chair device 17 above alluded to, and which consists of sides 18 to which the bars are secured at spaced points as shown at 19, preferably near the top edges thereof. Connecting the sides is a bottom portion or seat part proper 20, said sides being suitably braced in the relation specified, as by means of a cross member or brace 21 near the top and outer 100 end thereof and running transversely. The

seat or bottom 20 may be provided with a cushion 22 or the like, while the rear portion at the outer end thereof is cutout or away as shown at 23, for a purpose now to be described.

A back 24 is pivoted to swing between the sides 18, as shown at 25, said back being provided with a cushion 26, if desired, and having a frame portion surrounding the same and preferably of inverted U-shaped form, as shown, with the leg portions thereof apertured for pivotal mounting near the bottom edges of the sides, or bottom and outer or rear portion of the seat or chair, as described. The back or leg portions of the frame thereof extend below the bottom of the seat, through the cut-out or opening 23, and said lower ends are apertured and pivotally connected as shown at 26' to the rear ends of connecting rods or links 27, while the other or forward and inner ends of said rods are pivotally connected as shown at 28 to the upper arms or ends of levers 29 pivoted near their upper ends, as shown at 30, to brackets 31 secured beneath the seat bottom.

The other or lower long arms of the levers extend downwardly and are suitably formed for the supporting of a foot board or rest 32, said board or rest being adapted for vertical adjustment to suit the size of the occupant of the chair or seat. As shown, a brace or board 33 extends between and is secured to the long arms of the levers 29, and is slotted vertically at spaced points as shown at 34 to receive the horizontal threaded shanks 35 therethrough at right angles to the board, while wing or thumb nuts 36 are engaged thereon to hold the foot board or rest clamped in any desired position of vertical adjustment. It will also be observed that by reason of the pivotal or jointed connection of the back with the foot rest, as described, the back when in the position shown in Figure 1 of the drawings resting against the pins or brace 21 slightly inclined rearwardly, in sitting position, while the rest is positioned to receive the feet, may be swung downwardly to the position shown in Figure 2 of the drawings, against the seat bottom, in which case, the foot board or rest will swing upwardly out of the way and hidden from view, by reason of the rod 27, as it is thought will be clearly apparent from the drawings. In this position, the attachment or table appliance may be readily swung in or out for disuse or use as desired, slidably supported as stated. When the back is moved up in an upright position for use, the lower end thereof will move inwardly and by reason of the rod 27, the lever 29 will move vertically, the upper arm swinging upwardly and inwardly and the lower arm swinging downwardly and

outwardly. The foot board or rest may then be adjusted to suit the length of the legs of the occupant.

In Figure 5 of the drawings another form of foot rest or board support is shown, in which the levers 37 corresponding to the levers 29 are twisted at right angles below the pivots thereof as shown at 38 and apertured to receive clamping members or bolts 39 engaged by thumb or wing nuts 40. Right angular members 41 have the horizontal portions thereof connected by and provided with a foot board proper 42 while the vertical portions are provided with slots 43 through which the bolts or clamping members extend, in order to hold the foot rest in any position of vertical adjustment.

Thus, it will be seen that I have provided a very desirable device for the purposes stated.

Having thus described my invention, what I claim is:

1. In a chair attachment for a table having a top, a pair of supporting bars rigidly fastened in parallel relation to the under side of the table top and having longitudinal dovetail grooves in sides thereof and terminating inwardly of an edge of the table top, a chair of box-like form including a bottom with rigid side boards, supporting bars having their outer ends rigidly fastened to the upper portions of the side boards and formed with longitudinal dovetail ribs on the sides thereof snugly slidably engaging the grooves of the supporting bars, whereby the chair may be positioned by slideable movement under the table top or outwardly of the edge of the latter, at will, said chair further embodying a chair back pivotally mounted near its lower end between the side boards upon a horizontal axis so that the same may be folded outwardly and downwardly from a rearwardly inclined operative position to an inoperative position between the side boards below the upper edges of the latter, brackets rigidly fastened to the under side of the chair bottom near its forward edge, normally upright foot rest supporting levers pivoted near their upper ends to said brackets, and horizontal links pivotally connected at their ends to the lower end of the chair back and the upper ends of the levers beneath the chair bottom, whereby upward swinging movement is imparted to the foot rest upon folding of the chair back forwardly and downwardly between the side boards, thereby providing knee room beneath the table top for persons occupying a separate seat at the table.
2. A chair including a seat portion of box-like form having a bottom with rigid side boards, a chair back pivotally mounted near its lower end between the rear ends of

the side boards upon a horizontal axis so that the same may be folded forwardly and downwardly from a rearwardly inclined operative position to a folded inoperative position between the side boards below the upper edges of the latter, brackets rigidly fastened to the under side of the chair bottom near its forward edge, normally upright foot rest-supporting levers pivoted

5 near their upper ends to said brackets, and

horizontal links pivotally connected at their ends to the lower end of the chair back and the upper ends of the levers beneath the chair bottom, whereby the foot rest is swung forwardly and upwardly when the 15 back is swung forwardly and downwardly.

In testimony whereof I affix my signature.

HERBERT R. ELLIS.
